UNITED STATES PATENT OFFICE.

JOHN B. WATSON, OF TORONTO, AND JOSEPH R. DOUGLAS, OF OTTAWA,
CANADA.

VENTILATING AND FURNACE-CHECKING DEVICE.

SPECIFICATION forming part of Letters Patent No. 520,974, dated June 5, 1894.

Application filed February 1, 1894. Serial No. 498,715. (No model.)

To all whom it may concern:

Be it known that we, JOHN B. WATSON, of the city of Toronto, and JOSEPH R. DOUGLAS, of the city of Ottawa, in the Province of Ontario and Dominion of Canada, have jointly invented certain new and useful Improvements in Ventilating and Furnace-Checking Devices; and we do hereby declare that the following is a full, clear, and exact description 10 of the same, reference being had to the accompanying drawings, forming a part hereof.

Our invention, which will be hereinafter fully set forth and claimed, relates to devices for ventilating rooms warmed by, or in proximity to, a hot air furnace, water or steam 15 boiler and for controlling or checking said furnace or boiler.

The object of our invention is to provide ready means of changing the air in rooms 20 heated by, or in proximity to, a furnace or boiler and to control and check the fire in said furnace or boiler.

Figure 1 is a horizontal section through the ashpit of a furnace or boiler, on line *x x*, Figs. 25 2 and 4, showing our improvements. Fig. 2 is a side elevation corresponding to Fig. 1. Fig. 3 is a top view of the same. Fig. 4 is a rear elevation of the same. Fig. 5 is a transverse section through the ashpit mouth, on line *y y* Figs. 1, 2 and 3, showing the valve box 30 therein in longitudinal section, with the valve open and the fire drawing the air from the rooms connected for ventilation. Fig. 6 is a similar section of the valve box, showing the valve closed. Fig. 7 is a similar section 35 of the valve box, showing the valve closed set for checking the draft, and Fig. 8 is a perspective view of the valve box, corresponding to Fig. 7, parts being broken out.

Hot air furnaces, water and steam boilers, 40 all being for the present purpose essentially alike in construction, are represented by one of the former, A, in Figs. 1, 2, 3 and 4; A' being the ashpit and A'', Figs. 2, 3, 4 and 5, 45 the ashpit mouth with door.

In one side of the ashpit mouth is formed 50 an opening which is covered by one of the open ends of a valve box, B, rectangular in cross section, having its other end connected, 55 by means of pipes or ducts, D, Figs. 1, 2 and 4, to the room or rooms which it is desired to

ventilate. In said box is hung, at the top and extending down in the segmental bottom part, *b*, on an axle, C', which is journaled in the sides of the box and having its projecting 55 front end provided with a crank *c'*, a plate C forming a valve. This has at its rear edge a sector shaped extension, wing or back, *c'*, set at a right angle to it and adapted to completely or partly close or uncover an opening 60 *b'* in the lower segmental portion of the rear side of the box. Said opening, being provided with a nozzle B', is made to communicate with the smoke stack A''' by a connecting pipe, E, in lieu of the check damper 65 usually provided in the said smoke stack. A rod, chain or cord, F, secured to the crank *c'*, passes up to one of the rooms, from which the crank may be controlled. A slide, B'', is provided in the front of the valve box on 70 the same side of the valve C as the opening *b'*, so that if it be open, a current of air entering it may pass through said opening into the pipe E and smoke stack A'''. The relative position and adjustment of the valve C with 75 the crank *c'* and opening *b'* is such that when the latter is completely closed by the back *c'*, the valve is fully open and the crank at its greatest upward inclination with the horizontal, as shown in Fig. 5, all the air passing 80 through the duct D passing through the valve box and being drawn into the ashpit A'. The valve, however, may also be closed against the ashpit, so that no current can pass from the duct D through the box B into 85 the ashpit, and the opening *b'* be closed also, as shown in Fig. 6, by just lowering the crank *c'* a little. It may also occupy any intermediary position between the latter and that shown in Figs. 7 and 8, which show the 90 crank in its lowest position and the opening *b'* fully open but the box closed against the ashpit. The edge of the sector back *c'* forms a stop for the valve against the top of the valve box, and another stop, *b''*, may be provided for its opposite extreme position. If the air in the room thus connected becomes close, the chain or cord F is drawn up and the valve brought into the position shown in Fig. 5, when the draft of the furnace will 100 draw the air from the room through the duct D into the ashpit, thus increasing the draft.

of the furnace and causing new air to enter the room. If it is not desired to increase the draft of the furnace and consequently the production of heat, the valve is brought into 5 the position shown in Fig. 7 or any position intermediary between it and that shown in Fig. 6, when the draft of the chimney will exhaust the air from the room through the duct D, passing through the opening b', pipe 10 E and the smoke stack, at the same time checking the draft of the furnace. The slide B" may be used for summer ventilation of the furnace room. The arrows in the figures show the direction of the draft.

15 We claim as our invention—

1. In a ventilating and furnace checking device, the combination with the ashpit mouth of a furnace or boiler, of a valve box connected with said mouth, a duct connecting 20 said box with the room to be ventilated, a nozzle on the lower rear part of said box, a pipe connecting said nozzle with the smoke stack of the furnace, a valve having a sector shaped back at a right angle and hung at the 25 top of the box on an axle provided with a crank and said valve adapted to allow or interrupt a current passing through said box and to cover or uncover with its back the opening in the said nozzle, and a chain or rod 30 F adapted to operate said crank, substantially as set forth.
2. In a draft and check valve for a furnace

or boiler, the combination of a box rectangular in cross section having part of its bottom segmental longitudinally, an opening in the 35 lower part of one of the sides over the segmental bottom, a plate C hung at the top of the box and having a sector shaped back plate c at a right angle adapted to cover said opening, and a crank c' adapted to be operated by a cord chain or rod, substantially as 40 set forth.

3. In a draft and check valve for a furnace or boiler, the combination of a box B rectangular in cross section and having part of its 45 bottom segmental longitudinally, an opening b' in the lower part of one of the sides over the segmental bottom, a plate C hung at the top of the box adapted to sweep the segmental bottom and having a sector shaped 50 back c at a right angle adapted to cover said opening and a slide B" in the side of the box opposite to that in which the opening b' is located and on the same side longitudinally of the valve C as said opening, substantially 55 as set forth.

In testimony whereof we have signed in the presence of the undersigned witnesses.

JOHN B. WATSON.
JOSEPH R. DOUGLAS.
